UNITED STATES PATENT OFFICE.

CARL WINKLER, OF BERN, SWITZERLAND.

MACHINE FOR CASTING STEREOTYPE PLATES.

Application filed February 5, 1927, Serial No. 166,227, and in Germany May 18, 1925.

In making machines for casting stereotype plates of this type, as in all other branches of manufacturing, it is desirable to standardize as many parts as possible, so that in constructing the ordered sizes of machines, the parts can be taken from stock. The mould itself must be made specially, according to the size of the newspaper page. Up to the present the frame for carrying the mould and moving it to the outlet opening of the pot containing the molten metal had to be made specially as well.

According to my present invention this frame is also standardized for all sizes of newspapers. For this purpose the frame is supported by the furnace walls by means of, at least one, eccentric bush, on each side of the machine, seated in a hole of the furnace wall. By turning these bushes the frame can be brought into such positions that a mould of any of the sizes in question can be brought into the proper position in regard to the outlet opening of the pot. If two eccentric bushes are used, one seated in the other, one of the two is preferably used for fine adjustments.

On the drawing illustrating the invention by way of example, Fig. 1 is a side elevation of the mould frame with mould and Fig. 2 a section on the line A—B in Fig. 1.

Figure 3 is a vertical section of the machine, and Figure 4 is a front view thereof.

Referring to the drawing, A is a furnace, B the melting pot and C the mold.

The mould consists, as usual, of a core b fastened to the pivoted frame a and of a mantle c having guided up and down movement in said frame. The mantle e of the mold is guided in slots of the frame, not shown, and is moved up and down by the crank mechanism D connected with the mantle by links d² and operated by the motor E and upon the cranks d³ of which the members a² of the frame a are seated. The means for guiding and moving the mantle up and down forms no part of this invention, the same being old and well known. The inlet opening d of this mould is formed by the distance between the core b and mantle c, and in the casting position, this inlet opening d must always register with the outlet e of the pot B. The outlet e of the melting pot B and the inlet d of the

mold C are controlled by valves e² and c² respectively. The frame a is mounted on the furnace casing by means of eccentric bushes f and g at each side of the furnace. As shown, the members a² of the frame a are secured to the eccentric bushes g mounted in the eccentric bushes f which are mounted in furnace casing. By this means with moulds of all sizes the openings d and e can be brought into register by turning, on both sides of the machine, the eccentric bushes f into the corresponding angular position. Consequently, the frame a can be used for all sizes of mould.

By means of the eccentric bush g any differences at the ends of the mould can be made up for. The two eccentric bushes f, g, have flanges h, i with slots k, l, through which pass bolts m, n which are screwed into the furnace walls and eccentric bush f respectively, so that both bushes can be kept in the desired angular position. By loosening the screws m n, the bushes f can be turned by a suitable tool to bring them into the desired position.

What I claim and desire to secure by Letters Patent of the United States is:

1. A casting machine for stereotype plates, comprising in combination a furnace, a melting pot in said furnace, having a slot opening in the lower part thereof, a mould adapted to be brought into contact with said pot so that the outlet opening of said pot registers with the inlet opening of said mould, a frame to carry and move said mould, and an eccentric bush to pivot said frame, seated in the wall of said furnace on each side of the machine, substantially as, and for the purpose, set forth.

2. A casting machine for stereotype plates, comprising in combination a furnace, a melting pot in said furnace, having a slot opening in the lower part thereof, a mould adapted to be brought into contact with said pot so that the outlet opening of said pot registers with the inlet opening of said mould, a frame to carry and move said mould, an eccentric bush seated in the wall of said furnace on each side of the machine, and a second eccentric bush seated in each of said eccentric bushes to pivot said frame, substantially as, and for the purpose set forth.

3. In a machine for casting stereotype plates, a furnace, a melting pot in the furnace and having an outlet in its lower portion, a frame, a mold carried by the frame below the melting pot and having an inlet in its top adapted to register with the outlet of the melting pot, and means for pivotally and adjustably mounting the frame on the furnace, whereby different sized molds can be carried by the frame and their inlets brought ¹⁰ into register with the outlet of the melting pot.
- 5 In testimony whereof I have signed my name to this specification.

CARL WINKLER.
